UNITED STATES PATENT OFFICE.

AURELIUS LAGASSE, OF FALL RIVER, MASSACHUSETTS.

SNOW-MELTING MACHINE.

Application filed October 5, 1923. Serial No. 666,766.

To all whom it may concern:

Be it known that I, AURELIUS LAGASSE, a citizen of the United States, residing at Fall River, in the county of Bristol and State of Massachusetts, have invented certain new and useful Improvements in Snow-Melting Machines; and I do declare the following to be a full, clear, and exact description of the invention, such as will enable others skilled in the art to which it appertains to make and use the same.

The principal object of the present invention is to provide an improved form of snow melting machine adapted to be moved forwardly over a snow covered surface and embodying a hood to receive part of the snow, means for directing some of the snow onto the top of said hood, and means for highly heating said hood to melt the snow within the latter, as well as that upon its top.

A further object is to provide a snow melting machine of comparatively simple construction, which may be easily attached to and operated by a motor truck.

With the foregoing in view, the invention resides in the novel subject matter hereinafter described and claimed, the description being supplemented by the accompanying drawings.

Figure 1 is a top plan view partly in horizontal section, showing a snow melting machine constructed in accordance with my invention.

Figure 2 is a longitudinal sectional view as indicated by line 2—2 of Fig. 1.

Figures 3 and 4 are transverse sectional views as indicated by lines 3—3 and 4—4 of Fig. 2.

In the drawings above briefly described, the numeral 1 designates an elongated transversely arched hood which is open at its bottom and partly open at its front end, so as to receive snow as the hood is pushed forward. I prefer to provide the front end of the hood with supporting rollers 2, while its rear end may well be supported by the truck which is used to operate the device. In the construction shown, a transverse bar

3 is secured to the chassis frame of the truck and is formed with reduced ends 4 which pass through openings in the rear ends of the side walls 5 of said hood, nuts 6 being threaded on said bar ends to prevent accidental release of the hood. By removing these nuts however and spring-

ing the sides 5 outwardly, the entire hood may be detached from the truck.

The connecting means above described between the hood and the truck froms a pivotal mounting for said hood, permitting it to be swung upwardly whenever desired, for instance, when turning corners. For so swinging the hood, I have shown a pair of cables 7 connected to the front upper corners of the hood sides 5, said cables being inclined rearwardly to any suitable operating means carried by the truck.

At its front end, the hood 1 is provided with a forwardly declined plate 8 whose upper end coincides with the hood top 9. The lower end of the plate 8 is spaced above the lowermost plane of the hood and this plate is intended to direct some of the snow onto the hood top 9, while permitting the remainder of the snow, in the path of the hood, to enter the latter, provision being made for highly heating said hood to melt the snow both within the latter and on its top 9. In most instances, I prefer to mount an extension plate 10 on the lower end of the plate 8, said plate 10 being adjustable downwardly or upwardly according to the depth of the snow, and being entirely detachable if desired. I have shown lugs 11 on the plate 10 and similar lugs 12 on the lower end of the plate 8, and adjustable braces 13 which are connected with the sides 5 of the hood, may be connected with the ears 11 when the plate 10 is used, or with the ears 12 when said plate 10 is detached. These braces prevent bending of the plates, under the rearward thrust of the snow.

Under the plate 8, I preferably provide a transverse end wall 14 for the hood 1, the lower edge of said wall however being spaced upwardly a considerable distance from the lowest plane of the hood, to permit the snow to readily enter. The lower edge of the wall 14 is by preference provided with a vertically adjustable extension plate 15 which may be raised or lowered as desired. The wall 14 and plate 15, serve to trap heat and flame in the hood, which is also true of a rear end wall 16 with which the hood is provided.

Under the end wall 14, I preferably extend a transverse bar 17 across the hood 1, said bar carrying a plurality of forwardly extending teeth 18 for chipping frozen snow and ice, to facilitate melting thereof. The bar 17 may well be mounted so that it

can be removed, with the teeth 18, if its use is not necessary.

To facilitate the rearward passage of snow along the inclined plate 8, onto the top of the hood 1, I prefer to employ an endless conveyor which may be of any desired construction. In the present disclosure, a front transverse conveyor shaft 19, having sprockets 20, is rotatably supported above the front end of the plate 8, by suitable arms 21 extending forwardly from the sides of the hood. A rear conveyor shaft 22 having sprockets 23, is mounted over the rear portion of the hood 1, by suitable bearing arms 24, the sides 5 of the hood being preferably reinforced by suitable plates 25, where the arms 21 and 24 are secured to said sides.

Endless chains 26 are trained around the sprockets 20 and 23 and carry appropriate conveyor plates 27 which are adapted to carry the snow upwardly along the plate 8 and rearwardly along the top 9 of the hood 1. To properly guide the chains 26, I preferably provide upper and lower tracks 28 and 29 secured to suitable spacers 30 which are supported by transverse rods 31, said rods being in turn supported by arms 32 secured to the sides 5 of the hood.

Any desired means may be employed for driving the conveyor. I have shown one end of the shaft 22 provided with a sprocket wheel 33 engaged by a chain 34, said chain extending rearwardly and being adapted to be driven by any suitable means. A suitable clutch 35 may be provided for operatively connecting the sprocket 33 with the shaft 22, or for releasing said sprocket from the shaft, as occasion may require.

The hood structure is preferably such as to permit it to be readily disassembled for compact storage if desired. In the construction shown, the numerous parts are flanged and detachably bolted together. The top 9 is preferably formed of several sections as indicated in Figs. 1 and 2 and these sections are curved so that the top is transversely arched as disclosed in Fig. 3 to facilitate running of the melted snow water therefrom.

To effectively heat the hood 1 to melt the snow on the top of this hood, as well as that under the hood, I have shown liquid fuel burners 36 within the rear portion of the hood, each burner head having a fuel pipe 37 leading from a main fuel line 38, and a compressed air or steam pipe 39 leading from a second main line 40. By mixing the fuel with air or steam under pressure, a flame is forcibly projected within the entire interior of the hood to efficiently heat the latter to a high degree, as well as playing upon the surface of the snow within said hood. Obviously, suitable valves may be provided in the numerous pipes, at any desired or convenient points.

The operation of the invention is a simple matter. With the burners 36 operating, the hood is forced along the surface to be cleaned, by the motor truck, the plate 10 having been adjusted to the desired extent or entirely removed if advisable. It will be seen that some of the snow will be scooped up by the plate 8 and that the conveyor plates 27 will carry such snow rearwardly over the highly heated top 9 of the hood, so that it is properly melted. The remaining snow under the plate 8, enters the hood 1 and the flame within the latter, from the burners 36, quickly melts such snow. Except in unusually heavy snowfalls, the hood may be moved continuously forward and will melt the snow as it moves, the speed of travel being of course suitably synchronized with the melting ability of the device. When unusual snow banks are encountered, it may be necessary to momentarily halt the forward movement of the device to permit complete melting of the snow within and upon the same, but such occurrences are unusual.

When it is desired to turn the truck around a corner, the cables 7 are operated to swing the entire hood upwardly, so that it does not interfere with the turning operation. It may here also be stated that if the hood is to be moved idly from one point to another, it may be swung upwardly by means of the cables so that it will clear the roadway. If desired, when it is upwardly swung in this manner, a suitable truck (not shown) may be inserted under it. Then, the hood may be detached from the front end of the motor truck, and the latter turned around. Then, the hood can be coupled in any suitable way to the rear end of the motor truck and pulled as a trailer.

As excellent results may be obtained from the details disclosed, they may be followed if desired, but the present disclosure is principally for illustrative purposes and within the scope of the invention as claimed, numerous changes may be made.

I claim:

1. A snow melter comprising a transversely arched hood adapted to be moved along a snow covered surface, means at the front end of said hood and spaced above the lower plane thereof for directing the upper part of a blanket of snow onto the top of said hood and leaving the lower part of the snow blanket on its supporting surface, the front end of said hood being open below said means to cause said lower part of the snow blanket to enter said hood when the device is moved forwardly, and means for highly heating the hood to melt the snow on top of and within the same.

2. A snow melter comprising a transversely arched hood adapted to be moved along a snow blanketed surface, a forwardly

declined plate at the front end of said hood having its front edge disposed in a plane above the lowermost plane of said hood for directing the upper part of a blanket of 5 snow onto the top of said hood and leaving the lower part of the snow blanket on its supporting surface, the front end of said hood being open below said plate to cause said lower part of the snow blanket to enter 10 said hood when the device is moved forwardly, and means for highly heating the hood to melt the snow on top of and within the same.

3. A snow melter comprising a trans- 15 versely arched hood adapted to be moved along a snow blanketed surface, a driven conveyor over the top of said hood and declining at the front end of the latter to a plane spaced above the lowermost plane 20 of the hood, means for rearwardly driving said conveyor to carry the upper part of the snow blanket rearwardly onto said top and leave the lower part of said blanket on its supporting surface, the front end of said 25 hood being open under said conveyor to cause said lower part of the snow blanket to enter said hood when the device is moved forwardly, and means for highly heating the hood to melt the snow on top of and 30 within the same.

4. A snow melter comprising a trans- versely arched hood adapted to be moved along a snow blanketed surface, a forwardly declined plate at the front end of said hood 35 having its lower edge spaced above the lowest plane of the hood, the front end of said hood being open under said plate, a driven conveyor co-operating with said declined plate to feed the upper part of the snow

blanket rearwardly onto the top of the hood, 40 while leaving the lower part of said blanket on its supporting surface, the front end of said hood being open under said plate to cause said lower part of the snow blanket to enter said hood when the device is moved 45 forwardly, and means for highly heating the hood to melt the snow on top of and within the same.

5. A structure as specified in claim 2; 50 together with an extension plate mounted adjustably on said forwardly declined plate, and a vertically adjustable plate extending across the front end of said hood under said declined plate.

6. A structure as specified in claim 1; 55 together with a bar extending transversely across the front end of said hood and having forwardly extending teeth to break frozen snow and ice for more rapid melting.

7. A snow melter comprising a trans- versely arched hood adapted to be moved along a snow covered surface, a plate declining forwardly from the top of said hood to a point spaced above the lowest plane of said hood, a transverse conveyor shaft 65 mounted over the lower end of said plate, a second transverse conveyor shaft mounted over the top of the hood, an endless conveyor engaged with said shafts for carrying snow onto the top of the hood, tracks for 70 guiding said conveyor over said plate and said top, and means for highly heating said hood to melt snow both in the latter and on its top.

In testimony whereof I have hereunto 75 affixed my signature.

AURELIUS LAGASSE.
